Primary Examiner — Jack Reickel*Assistant Examiner* — Salamah Jordan(74) Attorney, Agent, or Firm — Schott, P.C.(57) CLAIM

The ornamental design for the weight vest, as shown and described.

DESCRIPTION

1. Weight vest

1.1 : Perspective

1.2 : Perspective

1.3 : Front

1.4 : Front

The design relates to an adjustable weight vest with a front pocket; reproduction No. 1.4 shows the weight vest with the straps in unfolded position; the dotted lines indicate elements for which no protection is sought and is not a part of the claimed design.

1 Claim, 4 Drawing Sheets(56)
